MATERIAL FORMING APPARATUS

James W. Juvinal, La Grange Park, and John S. Stull, Chicago, Ill., assignors to Western Electric Company, Incorporated, New York, N. Y., a corporation of New York

Application March 31, 1944, Serial No. 528,860

6 Claims. (Cl. 153—13)

1

This invention relates to material forming apparatus and more particularly to an apparatus for forming the leads on a stem of a vacuum tube.

An object of the present invention is the provision of a simple and practicable apparatus for efficiently and accurately forming the leads on a stem of a vacuum tube.

In accordance with the above object, the present invention, in one embodiment thereof, is applied to the forming of a plurality of leads extending from a glass supporting stem of a vacuum tube, wherein two aligned leads are to be similarly bent toward each other at points predetermined distances from their outer ends, and a third lead, which is offset and intermediate the other leads, is to be bent at two points predetermined distances from its outer end toward and in a plane at right angles to the plane containing the bent ends of both of the other leads so that its outer end terminates in alignment with the other leads.

Specifically, the lead forming apparatus of this invention comprises means for supporting the stem from which the leads extend, stationary and movable cooperating means for holding the three leads at predetermined bending points spaced inwardly from their free ends, and a longitudinally movable and laterally displaceable hollow bar having cam faces on its end face adjacent the free ends of the aligned leads, which cooperate with similar cam faces on the stationary holding means to bend the two leads. Longitudinally slidable in the hollow bar is a rod, into an aperture of which is inserted a predetermined length of the free end of the third lead. To double bend the third lead, the bar carrying the rod is first predeterminedly positioned and then displaced laterally by operating a cam lever, which effects the desired bending of the third lead, which extends into the rod, between the end thereof and an inner bending point on the holding means. This movement of the bar serves to align the cam faces thereon with the other two leads and, thereafter, a lever arranged in the path of a pin on the bar is operated to longitudinally move the bar to engage the cam faces thereof with the free ends of the two leads to bend them about their bending points arranged on and against the cam faces on the stationary holding means.

Other objects and advantages of this invention will more fully appear from the following detailed description taken in conjunction with the accompanying drawings, in which

Fig. 1 is a fragmentary plan view of a forming apparatus embodying the features of the invention;

Fig. 2 is a side view thereof;

2

Figs. 3 and 4 are perspective views of certain parts of the apparatus;

Figs. 5 and 6 are vertical sectional views taken on the lines 5—5 and 6—6, respectively, of Fig. 1;

Fig. 7 is an enlarged fragmentary plan view of Fig. 1, partly in section, showing the parts in position preparatory to the bending of the leads;

Fig. 8 is a fragmentary view, similar to Fig. 7, showing the parts after bending one of the leads;

Fig. 9 is a vertical section taken on the line 9—9 of Fig. 8; and

Fig. 10 is a vertical section taken on the line 10—10 of Fig. 7.

Referring to the drawings in detail and particularly to Figs. 1 and 7, a glass supporting stem of a vacuum tube is indicated at 15, in which are fused three lead wires 16, 17 and 18, which extend freely from the right end of the stem. Formed on the left end of the stem 15 is a flange 19. The leads are straight and of the desired length at the time the stem 15 is mounted upon the forming apparatus, as shown, to effect the desired bending operations on the leads. As shown in Fig. 10, the two leads 16 and 17 are arranged on the stem 15 in alignment and the lead 18 is offset therefrom and intermediate the other two leads. Also fused to and extending from the left end of the stem 15 is a glass tube 20. Threaded onto the leads before the bending operations and abutting the right end of the stem 15 is a radially slotted disc 22, which is part of the vacuum tube.

The lead forming apparatus comprises a channel-shaped base plate 23 supporting a standard 24 at its left end, which is pivoted at 25 and provided with a horizontal aperture 26 tapered outwardly at its right end for receiving and supporting the glass tube 20. At its right end, the tube 20 is supported in a forked rest 29 slidable horizontally on a standard 30. The stem flange 19, when the stem is mounted in position, is pressed at its left face against the rest 29 by a forked leaf spring 31 secured to the rest, the spring also serving to support the stem and its attached tube 20 in the desired longitudinal position on the apparatus.

To the right of the standard 30 is a standard 32, to the upper face of which is fixed a lead positioning and holding member 33 having formed in its inner end (Figs. 5, 9 and 10), which end is recessed and of irregular shape for clearance purposes, two spaced vertically aligned notches 36 for receiving the leads 16 and 17. The free ends of the leads 16 and 17 project freely from the notches 36, the inner ends of the notches terminating in oppositely sloping cam faces 38, against which the leads are formed to provide the desired bent portions 40 (Fig. 9) by means to be presently described. Longitudinally slidably mounted upon the standard 32 in a slideway 43

thereof and aligned with the member 33 is a multiple member assemblage comprising, in the main, two jaw-like members 44 and 45, the member 45 being guided for vertical movement upon the member 44 by means of loosely fitting dowel pins 46. The jaw-like members 44 and 45 are urged apart by a compression spring 47, when a thumb nut 50 is loosened upon a screw 51 fixed to the member 44. Inner horizontal faces of the jaw-like members 44 and 45 normally abut, as shown in Figs. 5 and 10, and the member 45 is formed with a notch 52 for receiving the lead 18, which, in the normal position of the members 44 and 45, is held therebetween and at which time the inner vertical faces of the members abut the opposed inner vertical face of the fixed member 33. One side of the notch 52 intermediate its length is cut away for clearance purposes to provide a vertical sloping face 53 (Figs. 7 and 8), which is substantially aligned with a similar face on the member 33. The juncture point of the sloping face 53 and the notch 52, indicated at 54, serves as a forming point for an inner bent portion 55 (Fig. 8) on the lead 18, which is effected by means to be presently described, the outer free end of the lead being the second bent portion thereon.

Fixed to the right end of the base plate 23 is a standard 56 having a vertical wall 57 extending longitudinally thereof (Figs. 1 and 6). Slidably longitudinally upon an upper face 58 of the standard 56 is a channel-shaped bar 59 and spanning and secured to the end faces of the channel arms is a vertical cover plate 60, the arrangement providing a square aperture 63 in which is freely fitted for longitudinal movement a round rod 64. The rod 64 projects from both ends of the bar 59 and at its right end has fixed thereto a knurled handle 65. Formed axially in the rod 64 at its left or inner end is an aperture 66 of suitable length and diameter to freely receive the lead 18. The inner end of the bar 59 is notched to provide sloping cam faces 67 complementary to the sloping cam faces 38 of the member 33 and each is formed with a lead locating groove 69 for receiving the free ends of the leads 16 and 17 as the bar is advanced toward the leads to bend the same in the operation of the apparatus to be presently described.

In the operation of the apparatus to form the double bend in the lead 18, which is entered in the aperture 66 of the rod 64, and assuming that the rod is in its advanced position abutting a stop pin 70 on the jaw member 45, the bar 59 is displaced laterally from the position thereof shown in Figs. 1 and 7 to that shown in Fig. 8 by a counter-clockwise rotation of a hand lever 71 pivoted at 72 on the standard 56 and having a cam fact 73 bearing on the cover plate 60 of the bar. This movement of the lever places the bar 59 firmly against the vertical wall 57 of the standard 56 and also aligns the lead locating grooves 69 in the bar with the leads 16 and 17 in preparation for the bending thereof. To advance the bar 59 while still maintained in its last described position against the wall 57, by means of the cam lever 71, a hand lever 74, pivoted at 75 on a standard 75 secured to the plate 23, is moved in a clockwise direction to engage a vertical pin 76 on the bar 59. This longitudinal advance of the bar 59 is shown in Fig. 9, wherein, in the broken outline position thereof, the leads 16 and 17 have been formed with the bent portions 40.

To mount a stem 15 on the apparatus, as shown in Fig. 1, the assemblage, comprising the jaw-

like members 44 and 45, which have been released by turning the thumb nut 50 to permit the spring 47 to raise the jaw member 45 from the jaw member 44, is slid on the slideway 43 to the right, as viewed in Fig. 5, to provide a suitable space between the inner opposed ends of the member 33 and the jaw-like members to permit and facilitate the entrance of the leads 16, 17 and 18 into position for bending. Also, at this time, the slidable forked rest 29 and spring 31 have been moved upwardly, as viewed in Fig. 1, out of the path of the stem and leads. Before mounting the stem 15 in position, the hollow bar 59, with the rod 64 therein, is slid to the right (Fig. 1) so that the end of the lead 18 will be entirely clear of the parts. Thereafter, the tube 20 attached to the stem 15 is inserted in the aperture 26 of the pivotal standard 24, which has been rotated slightly clockwise (Fig. 1) and slid therealong a suitable distance, which will permit the leads at the opposite end of the stem to clear the standard 32, the disc 22 being in position on the leads and abutting the right end face of the stem. The stem is then swung horizontally into such position that the leads 16, 17 and 18, upon longitudinal and rotary movement of the stem 15, will be accurately entered in the space between the opposed ends of the member 33 and the jaw-like members 44 and 45. Following this, the forked rest 29 and spring 31 are returned to the position shown in Figs. 1 and 7, wherein the spring is pressing the flange 19 of the stem against the rest 29. The jaw-like members 44 and 45 are then slid as a unit to abut the inner end face of the member 33 to lodge the leads 16 and 17 in the positioning notches of the member 33 and then the jaw member 45 is lowered by rotating the thumb nut 50 to lodge the lead 18 in the notch 52 of the jaw member 45.

With the stem 15 mounted in position, the bar 59 and the rod 64 are advanced to the left (Fig. 1) by means of the handle 65 on the rod to the position shown in Fig. 7 to enter the lead in the aperture 66 of the rod and abut the inner end face of the rod with the stop pin 70, which pre-determines the point about which the free end of the lead 18 will be bent about the bent portion 55 of the lead in the following operation. The cam lever 71 is then rocked counter-clockwise, which effects a lateral displacement of the bar 59 and rod 64 until the bar is pressed against the wall 57 of the standard 56. In this operation, as clearly shown in Fig. 8, the lead 18 is given two bends, one at the fixed forming point 54 to provide the portion 55 on the lead, and the other at the juncture of the free end of the lead with the end of the rod 64 where the lead enters the aperture 66 of the rod, the free end of the lead 18 now being in alignment with the leads 16 and 17. Also in this operation, the lead locating grooves 69 in the sloping cam faces 67 at the inner end face of the bar 59 are aligned with the leads 16 and 17. Thereafter, the rod 64 is preferably retracted into the bar 59 until its outer end face is to the right of the extreme outer end of the bent lead 18 an appreciable distance to insure that the rod in the following operation of bending the leads 16 and 17 will not be advanced with the bar 59 and tend to deform the bent lead 18. The lever 74 is now rocked clockwise (Fig. 1) to engage the pin 76 on the bar and by a continuing movement of the lever, the bar is advanced, although still being pressed against the wall 57 by the cam lever 71, to cause the leads 16 and 17 to enter the grooves

69 and, by means of the cooperating cam faces 67 on the bar and the cam faces 38 on the fixed member 33, the leads are bent to the positions shown in dotted outline in Fig. 9. This completes the bending operations on the leads 16, 17 and 18 and thereafter the stem 15 may be removed from the apparatus without deforming the leads by returning the various parts to their initial positions previously mentioned in describing the mounting of the stem on the apparatus.

To check the alignment of the outer end of the lead 18 with the leads 16 and 17 after the double bending operation on the lead 18, the rod 64 may be withdrawn from the end of the lead by a movement thereof to the right by means of the handle 65 and then advanced again to the left and if the lead enters the rod aperture 66, the lead is properly aligned with the other leads. In case the lead does not enter the aperture 66, it indicates imperfect alignment and it will need to be adjusted. This adjustment may be effected after loosening the bar 59 from the wall 57 by releasing the cam lever 71 sufficiently to permit a slight lateral movement of the bar between the wall and the cam lever and then grasping the handle 65 and by a lateral pull thereon to effect a rocking movement of the bar about the cam face 73 of the lever in one direction or the other until the lead 18 is in the desired alignment with the leads 16 and 17.

What is claimed is:

1. An apparatus for forming leads arranged in triangular position on the stem of a vacuum tube comprising a support having a bending point for each of said leads, a member having a pair of forming faces movable laterally into alignment with said leads and toward the stem for bending two of said leads toward each other in one plane, means for moving said member to bend said leads, a second member for receiving the end of a third lead and movable laterally thereof with said laterally movable first member to form a double bend therein, and means for moving said second member to form said third lead with the end of said lead parallel with the plane of said two leads.

2. In apparatus for forming leads arranged in triangular relation on the stem of a vacuum tube comprising a support having a bending point for each of said leads, a member having inclined faces at one end movable laterally into alignment with and engageable with the end faces of two of said leads for bending said leads toward each other in one plane, and a second member for receiving the end of a third lead and movable laterally thereof with said laterally movable first member to form a double bend therein with the end of said lead parallel with the plane of said two leads.

3. An apparatus for forming leads extending from a stem of a vacuum tube comprising means for positioning and holding the leads at predetermined bending points adjacent said stem, lead forming elements arranged one within the other and movable laterally and longitudinally of said leads, the inner element having an aperture for receiving a predetermined length of the outer end of a lead to be given a double bend, one bend being at one of said bending points and the other at the point where the lead enters said apertured element, means for laterally moving said elements to double bend said lead and to align lead bending faces on said outer element with said other leads, said faces cooperating with the other of said bending points to bend said other leads,

and means for longitudinally moving said outer element to bend said other leads.

4. An apparatus for forming leads extending from a stem of a vacuum tube comprising means for positioning and holding the leads at predetermined bending points spaced from their outer ends, a laterally and longitudinally movable lead forming element having an aperture for receiving a predetermined length of the outer end of a lead which is to receive a double bend, one of said bends being at one of said bending points and the other at the point where the lead enters said apertured element, means for moving said element laterally of the lead to double bend the same, said means including a second laterally and longitudinally movable lead forming element supporting said first element and having faces for engaging other leads which are aligned with the said leads when the first element is moved laterally, said faces cooperating with the other of said bending points to bend said other leads, and means for longitudinally moving said second element to bend said other leads.

5. An apparatus for forming leads extending from a stem of a vacuum tube comprising means for positioning and holding the leads at predetermined bending points spaced from their outer ends, inner and outer lead forming elements movable laterally and longitudinally of said leads, an abutment for limiting the longitudinal movement of said inner element in one direction, abutments for limiting the lateral movements of said outer element, the inner element having an aperture for receiving a predetermined length of the outer end of a lead which is to receive a double bend, one of said bends being at one of said bending points and the other at the point where the lead enters said apertured element, means for moving said elements laterally of the leads to double bend said one lead and to align lead bending faces on said outer element with said other leads, said faces cooperating with the other of said bending points to bend said other leads, and means for longitudinally moving said outer element to bend said other leads.

6. An apparatus for forming leads arranged in triangular relation on the stem of a vacuum tube comprising means for supporting and longitudinally positioning said stem, said means including a rotary member and a pair of reciprocable forked members in which the stem rests, one of said forked members being yieldable and arranged to predeterminedly longitudinally position the stem against said other forked member, a support having a bending point for each of said leads, a member movable into engagement with the end faces of two of said leads for bending said leads toward each other in one plane, and a second member for receiving the end of a third lead and movable laterally thereof to form a double bend therein with the end of said lead parallel with the plane of said two leads.
